UNITED STATES PATENT OFFICE

93,693

DESIGN FOR A COCKTAIL SHAKER

Charles E. Swann, Glencoe, Ill.

Application August 18, 1934, Serial No. 52,982

Term of patent 14 years

To all whom it may concern:

Be it known that I, CHARLES E. SWANN, a citizen of the United States, residing at Glencoe, in the county of Cook and State of Illinois, have invented a new, original, and ornamental Design for Cocktail Shakers, of which the following is a specification, reference being had to the accompanying drawing, forming part thereof.

The figure is a perspective view of the cocktail shaker, showing my design.

I claim:

The ornamental design for a cocktail shaker as shown.

CHARLES E. SWANN.
